US00D730906S

(12) **United States Design Patent**
Amit et al.

(10) **Patent No.:** US D730,906 S
(45) **Date of Patent:** ** Jun. 2, 2015

(54) **MOBILE DEVICE MODULE**

(71) Applicant: **Google Inc.**, Mountain View, CA (US)

(72) Inventors: **Gadi Amit**, San Mateo, CA (US); **Daniel J. Clifton**, San Francisco, CA (US); **Paul Eremenko**, Sunnyvale, CA (US); **Inbal Etgar**, San Francisco, CA (US); **Susan Elizabeth McKinney**, San Francisco, CA (US)

(73) Assignee: **Google Inc.**, Mountain View, CA (US)

(**) Term: **14 Years**

(21) Appl. No.: **29/495,477**

(22) Filed: **Jul. 1, 2014**

(51) LOC (10) Cl. **14-02**

(52) U.S. Cl.

USPC **D14/435**

(58) **Field of Classification Search**

(57) **CLAIM**

The ornamental design for a mobile device module, substantially as shown and described.

DESCRIPTION

FIG. 1 is a perspective rear view of a mobile device module. FIG. 2 is a rear view of the module of FIG. 1.

FIG. 3 is a front view of the module of FIG. 1.

FIG. 4 is a left side view of the module of FIG. 1.

FIG. 5 is a right side view of the module of FIG. 1.

FIG. 6 is a bottom view of the module of FIG. 1; and,

FIG. 7 is a top view of the module of FIG. 1.

The claimed design is illustrated as a module of a handheld electronic device, such as of a mobile telephone or tablet.

Broken lines and entirely unshaded portions contained within broken line are not claimed.

1 Claim, 3 Drawing Sheets
